UNITED STATES PATENT OFFICE.

WILLIAM S. SEYMOUR, OF KENOSHA, WISCONSIN, ASSIGNOR TO ZALMON G. SIMMONS, OF SAME PLACE.

MACHINE FOR SECURING FABRICS TO BED-BOTTOM FRAMES.

SPECIFICATION forming part of Letters Patent No. 357,343, dated February 8, 1887.

Application filed October 12, 1886. Serial No. 216,080. (No model.)

To all whom it may concern:

Be it known that I, WILLIAM S. SEYMOUR, of Kenosha, in the State of Wisconsin, have invented a new and useful Machine for Securing 5 Fabrics to Bed-Bottom Frames, of which the following is a specification.

The machine comprises a suitable support for the end rail of the mattress, means for holding it in place, means for holding the batten 10 in place, and a clamp or compressor and mechanism for operating the same; and the invention consists in the parts and combinations hereinafter described and claimed.

The accompanying drawings illustrate the 15 machine proper, in connection with a turn-table for manipulating the mattress.

Figure 1 is a side elevation. Fig. 2 is a portion of a plan of the turn-table and its support. Fig. 3 is a vertical central section. Fig. 4 is a 20 rear elevation, Fig. 5 is a front elevation without the turn-table.

The frame of the machine consists of uprights A and a cross-piece, A', preferably of cast-iron, and firmly bolted together at a a. The 25 cross-piece has a vertical flange, a', and a horizontal flange, a², forming a bed or support for the end rail of the mattress. The upper ends of the uprights serve as guides, between which the compressor A² plays up and down.

30 The compressor is operated by a screw-shaft, B, at each end, which passes through an opening in each end of the compressor provided with a corresponding female thread. The screw-shafts pass through openings in the cross-piece A', and are shouldered so as to prevent their being drawn through the openings. They are operated by corresponding gearing, B', at each end, which is employed to raise and 35 lower both ends alike, the screw upon one shaft being right and the other left hand.

The reverse movements of the compressor are effected by means of vibrating friction-pulleys C C, supported in a frame, C', which is pivoted at c to its supporting frame D, which 45 is bolted to the cross-piece A' and to the floor, as shown at d d, Figs. 3, 4.

A shaft, D', journalled in two of the uprights A, at d', carries a friction-pulley, D², upon the periphery of which the vibrating pulleys are 50 arranged to bear alternately. The vibrating pulleys are operated continuously by pulleys

C', over which belts C³ from the power-shaft overhead are passed, the belt upon one side being crossed and upon the other not crossed, so as to give motion in opposite directions. When 55 one of the vibrating pulleys is in contact with pulley D²—as the upper one—said pulley D² will be driven in one direction, and when the other is in contact it will be driven in the opposite direction. The vibration of the pulleys is effected by an eccentric-pin, c', working in a slot or opening, c², in the edge of the frame C', said pin being connected to a wheel or head, E, of a rock-shaft, E', supported or journaled in a projecting portion of the frame or other suitable 60 support, said rock-shaft having a lever, E², projecting to the front within reach of the operator, for rocking it suitably to produce the vibration of the pulleys, as desired.

The shaft D' has a pinion, b, at each end, 70 which engages with the gearing B', and operates the same to drive the screw-shafts.

On the front of the machine is attached a projection or leaf, a³, whose upper surface is level with the top of the flange a², and below 75 this leaf is a rock-shaft, F, journaled in plates or brackets f, which are attached to the cross-piece A' by bolts. This rock-shaft is provided with clamp-arms f', which are thrown upward by rocking the shaft through a crank or arm, 80 f², projecting therefrom, to which a rod, r, is attached, which connects with a pedal-lever, p, pivoted or fulcrumed on the floor near its center, so that when the pedal is borne down the opposite end will elevate the rod and rock the 85 shaft a quarter-round and so throw the points of the clamp-arms f' up toward the flange a'. Slots s are provided in the leaf a³, for the arms to work through.

A rock-shaft, F', is also provided, pivoted 90 at the ends in projections e and provided with clamp-arms f' and lever-connections, substantially the same as those of F, but with the arms acting downward instead of upward, the pedal-lever p' being pivoted at its end to the 95 floor and to the rod r' near the center, so as to change the order of leverage and produce a downward instead of an upward throw of the arms. The shaft F' is weighted on the side opposite to the arms f', so as to counterbalance them and keep them in their most elevated position when raised to that position.

The turn-table G is supported on a truck, G', which runs on a track or frame, G². The center piece, g, of the frame of the table is pivoted to a shaft or support extending upward from the truck at the center, and the under side is provided with rollers g', which rest on a circular flange or track, g², of the truck. The under side is also provided with a downwardly-projecting member, g³, provided with a set-screw, which is made to impinge upon the circular flange, in order to set or fix the turn-table temporarily to the truck.

The under side of the compressor is provided with a facing, e', which is shaped to fit the top of the batten.

The operation is as follows: The end rail, H, of the mattress-frame is placed on the leaf a³ or on the flange a² of the cross-piece, with one side against the flange a'. Then by pressing down on the pedal-lever p the arms f' of the rock-shaft F are brought up against it and hold it close against the last-mentioned flange. The fabric I on the table is now brought forward by moving the truck forward until the end of the fabric is properly adjusted on the rail. The batten h, which has had the nails i for fastening it to the end rail previously started or set in holes partly through the batten, is now adjusted on the fabric, and the arms f' of the upper rock-shaft, F', are turned down on it by pressing down on the pedal-lever p', to hold it in place, when by a movement of the lever E² in the proper direction the compressor is brought down and drives the nails home, at the same time pressing the parts of the mattress tightly together. The lever E² is then reversed, so as to raise the compressor. The clamp-arms f' are now re-

leased and the table run back, bringing along the end rail and batten thus attached to the fabric sufficient to enable the turn-table to turn half-way round, so as to present the opposite end of the fabric to the front of the machine, and the operation repeated for attaching the other end rail and batten. The machine is designed to be operated by two attendants, one standing on each side of the table, by the pedal-levers p p'.

Having thus described my invention, what I claim, and desire to secure by Letters Patent, is—

1. The combination of the bed or support a' a², the compressor A², screw-shafts B, and clamp-arms f', as and for the purpose specified.
2. The combination of pedal-lever, as p, rod, as r, rock-shaft, as F, clamp-arms f', and flange a', as and for the purpose specified.
3. The combination of the pivoted frame C', provided with pulleys C C, the shaft D', provided with pulley D² and pinions b b, the gearings B' B' and screw-shafts B B, and compressor A², as and for the purpose specified.
4. The combination of uprights A, cross-piece A', compressor A², screw-shafts B B, and gearings B' B', as and for the purpose specified.
5. The combination of uprights A, cross-piece A', compressor A², screw-shafts B B, gearings B' B', and operating mechanism consisting of vibrating friction-pulleys C C, pulley D², shaft D', pinions b b, and shifting device E, as and for the purpose specified.

WILLIAM S. SEYMOUR.
